CLAIM

The ornamental design for a control panel for a feed milling system, or the like, as shown and described.

DESCRIPTION

FIG. 1 is a front perspective view of the control panel for a feed milling system, or the like, showing my new design;

FIG. 2 is a front elevational view thereof;

FIG. 3 is a side elevational view thereof;

FIG. 4 is an opposite side elevational view thereof;

FIG. 5 is a top plan view thereof;

FIG. 6 is a bottom plan view thereof; and

FIG. 7 is a rear elevational view thereof.
